UNITED STATES PATENT OFFICE.

EDWIN E. SLICK, OF PITTSBURGH, PENNSYLVANIA.

CONTINUOUS LEER.

Application filed February 11, 1925. Serial No. 3,402.

This invention relates to improvements in glassware annealing leers of the continuous type and mechanism for charging the ware into the leers.

3 An object of this invention is to produce a simple yet efficient glassware annealing leer of the continuous type in which the ware is indirectly heated.

Another object of this invention is to produce a glassware annealing leer of the continuous type in which the heating unit not only efficiently heats the chamber through which the ware is conveyed, but in addition thereto, heats the traveling leer conveyor before it reaches the point at which the ware is placed thereon to a temperature substantially equal to that of the ware to be annealed.

20 A further object of this invention is to produce a glassware annealing leer of the continuous type and mechanism co-operating therewith of such construction and arrangement that the articles to be annealed are automatically distributed to and placed in 25 position upon the leer conveyor.

A still further object of this invention is to produce an automatic charging device for leers of the continuous type by means of which the articles to be annealed are gently 30 placed in position on the leer conveyor in close, but spaced, relation.

A still further object of this invention is to produce charging mechanism adapted for co-operation with a traveling leer conveyor 35 and which may be adjusted so as to accommodate articles of different shapes and sizes.

A still further object of this invention is to produce an automatic charging device for continuous leers by means of which spacing 40 of the articles upon the leer conveyor may be regulated in order to accommodate articles of different shape and size and in order to synchronize the charging device with glassware forming machines of different capacities.

45 These, as well as other objects which will appear to those skilled in the particular art to which this invention relates, I attain by means of the organized apparatus described in the specification and illustrated in the drawings accompanying and forming part of this application.

In the drawings, Figure 1 is a top plan view with a section thereof broken away, of an 50 organized apparatus embodying this invention.

This view graphically shows the position of the heating unit for the leer and its position with relation to the leer conveyor. Fig. 2 is a view in side elevation of the apparatus. Fig. 3 is a view in longitudinal section of the entrance end of the leer. This view graphically shows the position of the heating unit for the leer and 60 its position with relation to the leer conveyor. Fig. 4 is a sectional view taken on line 4-4 of Fig. 3. Figs. 5 and 6 are detail views showing the construction of the leer conveyor. Fig. 7 is a front view in elevation 65 of the organized apparatus. In this view, a portion of the front hood is cut away for the sake of clearness. Fig. 8 is an enlarged plan view of the entrance end of the apparatus and shows in top plan the charging 70 mechanism and the mechanism for transporting ware to the charging mechanism and Figs. 9 and 10 are enlarged detail views of portions of the charging mechanism.

The organized apparatus comprises the 75 leer proper the charging mechanism and mechanism for carrying or transferring glassware or glass articles from the forming machine or machines to the charging mechanism. The forming machine may be a 80 press machine, a blow machine or a press and blow machine.

The leer proper comprises a relatively long housing which forms a tunnel-like annealing chamber. This chamber is heated by indirect heat derived from a heating unit located adjacent the entrance end of the leer and positioned between the top and bottom 85 of the heating chamber.

An endless conveyor made up of relatively thin perforated sheet metal flights linked together is so supported and driven that the upper run of the conveyor which moves inwardly from the entrance end is located above the heating unit while the lower run 90 is located below the same. On account of this arrangement, the conveyor on its return movement as it approaches the entrance end of the leer is heated to approximately 95 the temperature of the ware as it reaches the leer from the forming machine.

The annealing chamber is of such length that the articles conveyed therethrough will be raised and maintained at annealing temperature a sufficient time to remove internal 100 strains and will then be gradually cooled before they reach the discharge end.

An endless belt conveyor is utilized for transferring articles from the forming machine to the leer charging mechanism. This 110

endless conveyor is so mounted and driven that it is capable of being swung to different positions in order to adapt it for co-operation with different forming machines.

- 5 The charging mechanism receives the articles carried to the leer by the conveyor belt and automatically distributes them in spaced relation and in regular rows upon the leer conveyor. The charging mechanism 10 may be adjusted so as to take care of different sized articles and may also be adjusted so as to synchronize with forming machines of different capacities. In other words, it can be so adjusted as to synchronize with a 15 forming machine making 16 articles per minute or with one making 20 articles per minute, etc.

The construction of the leer housing may, of course, be varied, but as shown in the 20 drawings, it preferably consists of brick side walls 15 which are supported on a suitable foundation and a roof 16 which is preferably flat.

The roof is supported by inverted T-sections 17, the ends of which are secured in the side walls. Tile 18 rest upon the flanges of the T-sections and support the brick or other heat insulating material forming the roof proper.

- 25 30 The heating unit or element which is located adjacent the entrance end 19 of the leer and between the upper and lower runs of the leer conveyor, is supported on flanged sections 20 which are arranged in parallel 35 relation and are anchored in the side walls. These sections may either be inverted T-sections or as shown in the drawings, each section may be composed of two angles placed side by side and preferably secured 40 together.

Asbestos boards 21 of the required size and thickness rest upon the flanges of sections 20 and form a foundation for the heating unit. The asbestos boards also serve to limit the 45 downward radiation from the heating unit.

The bottom of the heating unit is composed of tile 22 and the top of the unit is composed of similar tile 23. Fire bricks 24 serve to support the roof tile and are so 50 arranged as to provide a tortuous path in the nature of a checkerwork for the hot combustion gases.

The heater element reaches across the entire width of the annealing chamber and as 55 shown in Fig. 4, extends into the side walls 15. Openings 25, preferably two, arranged in staggered relation, extend through the side walls 15 at the inlet end of the annealing chamber and communicate with the interior of the heating unit. A burner nozzle 26 extends into each of these openings. The burners may be constructed so as to utilize either natural gas, producer gas or oil as fuel. The fuel is supplied through pipes 27 60 which connect with a suitable source of fuel

supply. Pipes 28 for supplying the burners with air connect to a suitable source of low pressure or fan air.

The hot gases of combustion pass through the tortuous interior of the heating unit to 70 the outlet end 29 which communicates with a suitable flue 30 connected to a stack (not shown). A damper 31 is provided for controlling flue 30.

The leer conveyor which is endless is made 75 up of a number of relatively thin perforated sheet metal flights 32 which are connected together by means of links 33 and pins 34. The links are bifurcated as shown in Fig. 5, and each of the pins carries a roller 35 80 mounted thereon between the furcate parts.

The upper run of the conveyor is supported 85 by parallel spaced channel sections 36 while the lower run is supported upon a series of rollers 37 supported within channel sections 38 extending along the bottom of the leer housing.

The forward end of the leer conveyor is supported upon two spaced sprocket wheels 90 39 (only one of which is shown) mounted upon a horizontal shaft 40. These are idler sprockets and the shaft supporting the same is mounted in bearings which are adjustable toward and from the leer entrance for the purpose of taking up the unnecessary slack 95 in the conveyor.

The opposite end of the leer conveyor is supported on sprockets mounted on a fixed shaft 41. This shaft by means of a motor 42, a suitable chain drive 43 and a Reeves variable speed transmission device 44 is rotated at the proper speed to secure the desired linear travel of the leer conveyor. The mechanism will preferably be so constructed that the linear travel of the leer conveyor may be varied from say 7 to 46 feet per hour. The speed of travel will be varied to suit different ware.

100 Channel sections 36 are supported on I-beams 45 which are anchored in the side walls 15. In order to secure the channel sections to the I-beams and at the same time allow for expansion due to temperature changes, the channel sections are loosely secured to the I-beams by screws 46 and cross member 47 which connect the screws below the I-beams. The heads of screws 46 are countersunk in the web of the channel sections.

105 The upper run of the leer conveyor rolls along channel sections 36 during movement of the conveyor from the entrance to the outlet end of the leer chamber. The flights of the upper run are supported in the center throughout the length of the heating unit by means of a center support bar 48 with which the flights make sliding contact. On the return movement, the bottom run of the conveyor rolls along rollers 37.

110 115 120 125 130 The upper run of the conveyor forms a

flat moving apron or bed extending substantially the full width of the annealing chamber and from the entrance to the outlet end of the apparatus.

5 A hood 49 provided with windows or peep holes 50 and swinging doors 51 covers the entrance 19 to the leer chamber and prevents the escape of heat. Another hood 52 extends from hood 49 to the base of the apparatus 10 and covers the forward end of the conveyor.

The hoods are preferably made of sheet metal and one or both may be lined with heat insulating material.

15 The charging mechanism for the leer comprises an endless metal belt-like member 53 that encircles the upper run of the leer conveyor just in front of entrance 19 to the annealing chamber. A door or opening 54 is provided in one side of hood 49 over the 20 upper run of this belt-like member 53. This opening serves as an entrance for the articles to be annealed.

25 Belt-like member 53 is preferably spun from seamless steel tubing and is relatively thin and flexible. It is mounted on two pulleys 55 and 56 carried on parallel horizontal shafts 57 and 58 located on opposite sides of the apparatus. The pulleys are so positioned that the upper run of belt 53 lies in 30 substantially the same plane as the upper surface of the upper run of the leer conveyor so that articles moved laterally from belt 53 onto the leer conveyor will not be tipped to any appreciable extent. Shaft 57 which 35 at one end carries pulley 55 at the other end is provided with a mitre gear 59. This gear meshes with a gear 60 carried at the lower end of a vertical shaft 61. Shaft 61 extends upwardly above the top of the apparatus 40 and at its upper ends carries a mitre gear 62. A suitable electric motor 63 located upon the top or roof of the apparatus is utilized to drive the charging mechanism and the mechanism for conveying the articles to the 45 charging mechanism. The shaft of this motor is coupled to a worm that meshes with a worm wheel located within a housing 64 and a gear 65 on the worm wheel shaft which 50 meshes with gear 62 drives shaft 57 which carries pulley 55. Pulley 56 is an idler pulley and the support 66 within which this shaft is journaled is movably mounted so 55 that pulley 56 can be moved laterally of the apparatus to adjust the tension of the charging belt 53.

The articles to be annealed are carried from the forming machine or machines to the charging conveyor 53 by means of an endless belt conveyor 67. This conveyor is mounted on two pulleys 68 and 69 of which the latter is an idler pulley. Pulley 68 is keyed to a shaft 70 and the inner end of this shaft carries a mitre gear 71 that meshes 60 with gear 60 carried at the lower end of vertical shaft 61.

The support 72 within which shaft 60 is journaled is mounted for movement about a vertical stud 73 which is in axial alignment with vertical shaft 61. Support 72 is locked in position upon a base member 74 by means 70 of bolts 75 which extend through slots 76 formed in the support member 72.

A channel section 77 extends between pulleys 68 and 69 for conveyor belt 67 and the web of the section forms a support for the 75 upper run of the conveyor belt. This channel is supported by means of suitable upright supports 78 which can be moved to different positions upon their supporting foundation. The flanges of the channel section 77 form 80 side members for preventing the articles carried by the conveyor belt 67 from moving laterally off the belt. It will be seen from this construction that if it is necessary to swing the conveyor belt 67 to one side or the other in order to accommodate the forming machine, this can be done because of 85 the mounting device for shaft 70 which carries pulley 68. The lower run of conveyor belt 67 is supported upon rollers 79 carried in brackets 80 depending from channel section 77.

A circular transfer plate 81 formed of 90 relatively thin metal is mounted upon a vertical stud carried by a support plate 83 secured to support post 84 which is the end post of the series of support posts 78.

Transfer plate 81 is positioned between 95 the upper run of charging conveyor 53 and the upper run of conveyor belt 67 and contacts with both of these belts so as to be 100 rotated thereby. The linear speeds of charging belt 53 and conveyor belt 67 are the same. Channel section 77 terminates just short of transfer plate 81 and two parallel guide members 85 and 86 connected to the flanges 105 of channel section 77 are curved over transfer plate 81 and extend into opening 54 in the side of hood 49. These guide members compel the article to move off conveyor belt 67 and onto transfer plate 81. They also 110 compel the articles to leave the transfer plate and move onto the charging conveyor 53.

The mechanism for transferring the articles from charging conveyor 53 onto the 115 leer conveyor comprises a displacer or plough member which reciprocates back and forth across the leer conveyor above the charging conveyor. The construction of the mechanism is such that the displacer when moving in the same direction as the upper run of the charging conveyor travels at the same speed as the charging conveyor and when moving in the opposite direction, travels at a reduced speed which depends upon the width of the leer conveyor and the number of articles per minute arriving at the transfer plate.

The displacer mechanism comprises a displacer member 87 having an operating face 120

88 inclined to the line of travel of the charging conveyor 53. The displacer member is mounted to slide upon a rod 89 which extends across the leer conveyor and at its opposite ends is supported by the ends of hood 49.

A cable 90 preferably a flexible wire cable, attached at a point intermediate its ends to the displacer member, at one end which is 10 free, carries a weight 91. The cable passes over a rope pulley 92 located in the same horizontal plane as displacer 87.

The displacer operating mechanism comprises a rigid channeled support 93 and a 15 pivoted channeled support 94. Loosely mounted upon a shaft 95 secured within the flanges of channeled support 93 is a series of rope sheaves or pulleys 96 (the structure of the drawings includes four such sheaves). 20 A similar series of rope pulleys or sheaves 97 is loosely mounted on a shaft 98 carried within the flanges at the top of pivoted support 94. Cable 90 passes around the two series of sheaves and has its end 99 secured 25 to fixed support arm 93.

A cam 100 keyed to a shaft 101 which is journaled within bearings formed in the flanges of fixed support arm 93 during rotation causes support arm 94 which may be 30 termed a fulcrum arm to swing back and forth on its pivot 102. A contact roller 103 carried by the fulcrum arm bears on the outer periphery of the cam.

A cable 104 at one end is attached to the 35 fulcrum arm and passes over a sheave 105 and at its free end carries a weight 106. This weight tends to move the fulcrum arm 94 away from cam 100 and therefore relieves the cam of part of its burden during the separation of the two series of sheaves 96 and 40 97. Weight 91 which moves the displacer on its return stroke compounds the pounds tension through sheaves 96 and 97 (as in an ordinary rope block and tackle) to such an extent that a counterbalance weight 106 for 45 the fulcrum arm is desirable.

Cam shaft 101 is driven by a motor 107 through the instrumentality of gear 108 and a Reeves variable transmission device 109.

50 Weight 91 is sufficiently heavier than weight 106 to cause contact roller 103 to at all times remain in contact with the cam. The cam which rotates in the direction of the arrow (Fig. 9), is provided with a fall 55 110 which is so designed as to allow a quick movement of fulcrum arm 94 toward fixed arm 93 and the displacer 87 is so positioned on cable 90 that its quick movement will occur when the displacer reaches the limit 60 of movement of its travel toward transfer plate 81. This allows the displacer under the influence of weight 91 to be carried across the leer conveyor at a rapid speed. The mechanism is preferably so designed 65 that the displacer during its rapid move-

ment will travel at the same speed as the charging conveyor belt.

The movement of the displacer during its return or operating stroke is controlled by the number of sheaves carried by the fixed 70 arm 93 and the fulcrum arm 94 and the maximum stroke of the fulcrum arm. Every complete loop of cable 90 about the sheaves 96 and 97 multiplies the stroke of the fulcrum arm by two and the distance the displacer travels during its reciprocation depends upon the number of complete loops of the cable. The movement of the displacer may be increased by adding loops or decreased by subtracting loops. 80

The speed of travel of the displacer during its operating stroke (when moving counter to the upper run of the charging conveyor) depends upon the speed of rotation of cam 100 and its speed may be varied by 85 adjusting the Reeves variable transmission 109. During each complete revolution of the cam, the displacer will make one complete movement forward and back across the leer conveyor and as before said, the return or idle stroke of the displacer is controlled by the fall provided on the cam which is 90 preferably so designed that the linear speed of the displacer on its return stroke equals the linear speed of the charging conveyor 95 belt 53.

If the apparatus is to be used in connection with a forming machine adjusted so as to turn out 20 complete articles per minute, it will be desirable to operate the charging conveyor at a speed of 100 feet per minute and since the transfer conveyor 67 is driven at the same linear speed as the charging conveyor and the transfer plate is rotated by these two conveyors, articles will pass into 100 the apparatus at the rate of 20 per minute arranged at regular intervals of 5 feet. If the forming machine has a greater capacity than 20 per minute, the distance between the articles will be proportionately less. If 105 the leer conveyor is 60 inches wide and the articles produced by the forming machine are 3 inches in diameter (such, for instance, as tumblers) and the capacity of the forming machine is 20 per minute, the displacer 110 on its operating stroke will move at the rate of 3 inches for every five feet of linear travel of the charging belt. With the displacer moving at a speed of 3 inches for every five feet of linear travel of the charging belt, the displacer will displace 20 articles in a 115 row across the leer conveyor during each charging stroke. When the 20 articles have been displaced or pushed from the charging conveyor onto the leer conveyor the fall on the cam will allow the displacer to be returned by weight 91 to starting position. 120

In accordance with the provisions of the patent statutes I have described and illustrated but one embodiment of my invention, 125 130

it will be apparent to those skilled in the art that various changes, additions, substitutions and modifications may be made in the apparatus illustrated without departing 5 from the spirit and scope of this invention as set forth by the appended claims.

I claim:

1. The combination with a leer conveyor, of a charging conveyor movable across the 10 leer conveyor, means for conveying articles to the charging conveyor, a displacer for moving one article at a time from the charging conveyor to the leer conveyor and means for causing the displacer to move at one 15 speed while transferring the articles from the charging conveyor and at another speed while returning to initial position.

2. The combination with a leer conveyor, of a charging conveyor, means for carrying 20 articles to the charging conveyor, a displacer movable across the leer conveyor above the charging conveyor for transferring one article at a time from the charging conveyor to the leer conveyor and means for causing the displacer to move at one speed while transferring articles from the charging conveyor and at a greater speed while returning to initial position.

3. The combination with a leer conveyor, 30 of a charging conveyor, a conveyor for loading the charging conveyor and a transfer table between the loading conveyor and the charging conveyor and frictionally driven thereby.

35 4. The combination with a cable, of weighted means for moving the cable lengthwise in one direction, multiple series of sheaves encircled by said cable, supports for said sheaves and a cam so shaped as to periodically separate said supports and cause the cables to travel at a greater speed while moving in one direction than in the other.

5. The combination with an endless leer conveyor, of a charging conveyor, a displacer 45 for moving articles from the charging conveyor to the leer conveyor mounted for reciprocation above the charging conveyor, and means for causing said displacer to move in one direction at at least the same speed as the charging conveyor and in the opposite direction at a reduced speed.

6. The combination with an endless leer conveyor, of an endless charging conveyor, a displacer for moving articles singly from the 55 charging conveyor to the leer conveyor said displacer being mounted for reciprocation above the charging conveyor and means for causing said displacer to move in one direction at at least the same speed as the charging conveyor and in the opposite direction at a reduced speed.

7. The combination with an endless leer conveyor, of a rotatably mounted table, a carrier for delivering ware to the table, a 60 second carrier for receiving ware from the

table, a reciprocating displacer for moving ware from said second carrier to the leer conveyor, means for angularly adjusting the second carrier with respect to said table and means for guiding the ware to and from said 70 table to transfer it off one carrier and onto the other, said table projecting between said carrier whereby it is frictionally driven thereby.

8. The combination with a displacer 75 mounted for reciprocation, of a cable attached thereto and at one end secured to a fixed support, multiple sheaves arranged in two parallel series and encircled by said cable and means for periodically moving said series of sheaves toward and from each other.

9. The combination with a displacer mounted for reciprocation, of a cable attached thereto and at one end secured to a fixed support, multiple sheaves arranged in 85 two parallel series and encircled by said cable, and a cam for periodically moving said series toward and from each other.

10. The combination with a displacer mounted for reciprocation, of a fixed support, a pivoted support, a series of sheaves carried by each support, a cable attached to said displacer encircling said sheaves and having one end secured to a fixed support and a cam for reciprocating said pivoted support. 95

11. The combination with a displacer mounted for reciprocation, of a fixed support, a pivoted support, a series of sheaves carried by each support, a cable attached to said displacer encircling said sheaves and having one end secured to a fixed support, a cam for reciprocating said pivoted support and a weight secured to the free end of said cable. 100

12. The combination with two angularly disposed endless conveyors, of a rotatably mounted table projecting between the upper runs of said conveyors and driven thereby and means for guiding articles from one conveyor to the other by way of said table. 105

13. The combination with two angularly disposed endless conveyors, of a rotatably mounted table projecting between the upper runs of said conveyors and driven thereby and means for guiding articles from one conveyor to said table and from said table to the other conveyor. 115

14. The combination with two endless conveyors the major axes of which are angularly disposed one to the other, a transfer table frictionally driven by said conveyors, means for guiding articles from one conveyor to the other by way of said table and means for adjusting the angularity of one of said conveyors with respect to the other. 120

15. The combination with a leer conveyor, of two endless conveyors one of which crosses the leer conveyor, a transfer table frictionally driven by said angularly disposed conveyors means for guiding articles onto and 125

- from said transfer table and displacer mechanism for moving articles to the leer conveyor from the conveyor crossing the same.
16. The combination with a cable movable lengthwise in one direction by a weighted member, of a pair of relatively movable levers, sheaves carried by said levers and encircled by said cable and a cam for periodically separating said levers to move said
- 10 cable in opposition to said weighted member and at a different speed from that caused by said weighted member.
17. The combination with a cable movable

lengthwise in one direction by means of a weighted member, of relatively movable lever 15 arms, cable supports carried by said lever arms and encircled by said cable and a rotatable cam for periodically separating said lever arms whereby said cable is moved in opposition to said weighted member and at 20 a lower speed than that caused by said weighted member.

In testimony whereof, I have hereunto subscribed my name this 4th day of February, 1925.

EDWIN E. SLICK.
